UNITED STATES PATENT OFFICE.

OSCAR COUCH, OF LOS ANGELES, CALIFORNIA.

DESIGN FOR A MARMALADE JAR.

Application filed June 18, 1924. Serial No. 9,896. Term of patent 7 years.

To all whom it may concern:

Be it known that I, OSCAR COUCH, a citizen of the United States, residing at Los Angeles, in the county of Los Angeles and State of California, have invented a new, original, and ornamental Design for Marmalade Jar, of which the following is a specification, reference being had to the accompanying drawing, forming part thereof.

In the drawing:

I claim:

The ornamental design for a marmalade jar, as shown.

OSCAR COUCH.
